MACHINE ATTACHED BUTTON

Forrest G. Purinton, Middlebury, Conn., assignor
to The Patent Button Company, Waterbury,
Conn., a corporation of Connecticut

Application August 6, 1952, Serial No. 302,875

3 Claims. (Cl. 24—94)

1

This invention relates to buttons and pertains more particularly to a machine attached button in which portions thereof confront under compression both sides of the fabric to which the button is to be attached.

One important object of the invention is to provide a heavy duty button that is economical to manufacture, constructed of few parts and which will effectively resist detachment from the fabric to which it is secured.

Another object of the invention is to provide a button in which the gripping action is distributed over a relatively large area of the fabric.

A further object of the invention is to provide a button of lightweight construction that can readily be fabricated from relatively thin gauge sheet stock.

A further object of the invention is to eliminate the necessity of incorporating into the head thereof an anvil as is required in the well-known tack type of button.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing:

Fig. 1 is a plan view of the button attached to a piece of fabric;

Fig. 2 is an elevational view, partly in section, showing the parts of the anchor member just prior to attachment to a piece of fabric;

Fig. 3 is a sectional view taken in the direction of line 3—3 of Fig. 1;

Fig. 4 is a bottom view of the button; and

Fig. 5 is a perspective view of the two individual button parts depicted in Fig. 2.

Referring to the drawings, wherein one embodiment of the invention is illustrated, the button comprises a head A and an anchor member B by means of which the head is secured to a fabric C such, for example, as the material of which overalls, work shirts, etc. are made.

The head A is formed of two pieces, namely, a cap 12 and a body member 13. The body member has a dished flange portion 14 provided with a depending tubular shank 15 which terminates at its lower end in a generally laterally extending flange 16. This flange is transversely curved outwardly and upwardly so as to provide in its upper surface an annular groove 17 extending around the base of the shank. The cap is in

the form of a round, somewhat domed disc with its edges bent around the edges of the portion 14 of the body member. It will be seen that the head comprises only two parts, each of which is composed of sheet metal, and these parts can be very easily manufactured and assembled by simple operations.

The anchor member B, shown in Figs. 2 and 4, comprises a ring 20 provided with attaching prongs 21 and intervening backing prongs 23 extending from the inner edge of the ring. The outer peripheral portion of the ring is curved upwardly so that the under side of the ring presents a ringlike surface convex in cross section.

The prongs 21 are circumferentially spaced apart and extend upwardly. These prongs are tapered and their outer ends are V-shaped or pointed so as to provide piercing points 22 which may be pushed through the piece of fabric C to which the button is to be attached. The backing prongs alternate with the piercing prongs and the backing prongs extend inwardly towards the center of the ring but are slightly curved upwardly. It is clear that the anchor member B may be very

readily formed by simple stamping and bending operations. The attaching prongs are of such length that during the stamping operation these prongs extend to the center of the anchor member. The backing prongs are shorter than the

attaching prongs and they are of generally V-shape. Thus, the ring may be stamped from the disc and the disc simultaneously slit through the center so as to form the prongs. The prongs may be bent into the position shown in Fig. 2.

In attaching the parts of the button to the fabric C, the head and the anchor member are positioned at opposite sides of the fabric in proper alignment and then these parts are relatively forced towards each other so that the attaching prongs 21 pierce the fabric, and the fabric between the bottom surface of the flange 16 and the top surfaces of the backing prongs is compressed. The end portions of the prongs 21 are then, by means of suitable dies, curled or rolled inwardly and downwardly as shown in Fig. 3. During this operation the backing prongs are drawn towards the flange 16. It will be observed from Fig. 3 that the upstanding portions of the attaching prongs 21 are in engagement with the rim or periphery of the flange 16, and the ends of these prongs engage within the groove 17 of the flange 16, thus providing a very secure attachment between the head A and the anchor B whereby these parts are held against movement relative to one another. The underside of the ring 20, being curv-

ed, is relatively smooth, and the backing prongs 23 are curved slightly upwardly above the bottom plane of the ring. Thus injury or irritation to the wearer and any chance of the prongs catching on adjacent clothing or the like are avoided.

As many changes could be made in the above construction and many apparently widely different embodiments of this invention could be made without departing from the scope thereof, it is intended that all matter contained in the above 10 description or shown in the accompanying drawings shall be interpreted as illustrative, and not in a limiting sense.

It is also to be understood that the language used in the following claims is intended to cover 15 all of the generic and specific features of the invention herein described and all statements of the scope of the invention which, as a matter of language, might be said to fall therebetween.

I claim as my invention:

1. A button of the character described, comprising a head having a shank provided at its lower end with an outwardly extending flange, the bottom surface of which is adapted to confront one side of the material to which the button is to be attached, and an anchor member having a ring provided with integral backing portions extending inwardly from its inner edge for confronting the opposite side of the material, said ring also having spaced apart integral attaching prongs extending from its inner edge, positioned about said flange and having their upper ends curled inwardly towards said shank and downwardly into engagement with said flange for securing the parts together. 25

2. A button of the character described comprising a sheet metal head having a depending

hollow shank provided at its lower end with an outwardly extending flange, the bottom of which flange is adapted to confront one side of the material to which the button is attached, and a sheet metal anchor member having a ring provided with integral prongs extending inwardly from its inner edge for confronting the opposite side of the material, said ring having spaced apart integral attaching prongs extending upwardly from its inner edge, positioned about said flange and having their upper ends curved inwardly and downwardly to provide rolled portions engaging the upper surface of said flange for securing the parts together.

3. A button of the character described comprising a sheet metal head having a depending tubular shank provided at its lower end with an outwardly extending, upwardly curved flange with a groove in its upper surface, a sheet metal anchor member comprising a ring provided with integral backing prongs extending in spaced apart relation inwardly from the inner edge of the ring, said ring also having integral attaching prongs located between said backing prongs and extending upwardly from the inner edge of said ring and positioned about said flange, the upper ends of said attaching prongs being curled inwardly toward the shank and downwardly to provide rolled portions engaging the surface of the groove for securing the head and anchor member together with the material to which the button is to be attached compressed between the lower surface of the flange and the top surfaces of said backing prongs. 30
